UNITED STATES PATENT OFFICE.

CARL BRAMMING, OF CHICAGO, ILLINOIS, ASSIGNOR TO ACCESSORIES MANUFACTURING CO., A CORPORATION OF ILLINOIS.

COMBINED ELECTRIC CONNECTOR AND SWITCH.

1,323,822.

Specification of Letters Patent.

Patented Dec. 2, 1919.

Application filed May 3, 1917, Serial No. 166,236. Renewed October 6, 1919. Serial No. 328,929.

To all whom it may concern:

Be it known that I, CARL BRAMMING, a citizen of the United States, and resident of Chicago, county of Cook, and State of Illinois, have invented certain new and useful Improvements in Combined Electric Connectors and Switches, of which the following is a specification, and which are illustrated in the accompanying drawings, forming a part thereof.

The invention relates to connectors of the plug and socket type especially adapted for carrying an incandescent bulb; its object being to provide simple and effective means for connecting the leading-in wire with the lamp or other terminal, and arranged to close and open the circuit by alternate in-thrusts of the terminal plug or plunger.

The invention is a specific application of the switch forming the subject of a co-pending application to a connector; and it consists of a structure such as is hereinafter described and as illustrated in the accompanying drawings, in which—

Figure 1 is a longitudinal central section of the device showing the circuit closed;

Fig. 2 is an elevation of the device; and

Fig. 3 is a longitudinal central section showing the circuit open.

The body of the connector takes the form of a tubular socket 10, within one end of which is received and retained by a bayonet joint a terminal plug 11, shown as being the base of an incandescent lamp and having a central contact element 12. Within the tube 10 is fixed a block 13 of insulating material, through which is set a fixed tube 14 provided at each end with reciprocating contact elements 15, 16, between which re-acts an expansive spring 17.

A plunger 18 reciprocates within the opposite end of the tube 10, and is provided with an axial conductor 19, socketed at its outer end, as shown at 20, to receive a lead-ing-in wire. A spring seat 21 is mounted upon the inner end of the conductor 19, and an expansion spring 22 reacts between this seat and the block 13.

A disk 23 is mounted upon the conductor 19 back of the spring seat 21, and is preferably rotatable with reference to the plunger 18. A pair of studs, as 24, only one of which appears in the drawings, project radially from the margin of the disk 23, each coöoperating with a detent 25 for holding the

plunger at its inner position against the effort of the spring 22, in which position the circuit is closed by engagement of the conductor 19 with the contact element 16.

A series of cams are formed in the wall 60 of the tube 10 for coöoperating with each of the studs 24, for so positioning each as to pass the detent as the plunger moves inwardly, to cause its engagement with the detent as inward pressure upon the plunger 65 is relieved, and to disengage it from the detent at the next inward movement of the plunger, to permit it to pass the detent as the plunger moves outwardly when the pressure thereon is relieved. These cams are 70 preferably formed by aperturing the wall of the tube, as shown at 26. When the plunger is in its outer position the stud engages the outer end 27 of the aperture. As the plunger approaches the inward limit of its 75 movement the stud is engaged by an oblique cam edge 28 of the aperture and shifted laterally. As pressure upon the plunger is relieved the stud comes into engagement with the detent 25, which is preferably 80 formed as a bridge crossing the aperture 26. The edge of the detent with which the stud comes into engagement is oblique, and still further deflects the stud laterally, carrying it beyond the apex of a tongue 29 projecting 85 outwardly from the inner end of the aperture. Upon the next in-thrust of the plunger the stud comes into engagement with an oblique edge 30 of this tongue, and is still further deflected laterally to bring it out of 90 line with the detent.

Pressure upon the plunger being relieved it moves outwardly to its original position, the stud coming into engagement with an oblique cam edge 31 of the aperture 30 and 95 being deflected laterally in the opposite direction to so position it that at the next in-thrust of the plunger it will pass the detent. The bridge constituting the detent 25 is looped or bowed outwardly at its ends, as 100 shown at 32, 33, to provide ways for the passage of the stud 24.

While an efficient and preferred embodiment of the invention is shown and described, various changes of detail may be 105 made without departing from its scope.

I claim as my invention—

1. In a combined electric connector and switch, in combination, a socket, a fixed abutment therein, a spring-advanced contact 110

carried by the abutment, a spring-retracted terminal plunger reciprocable in the socket and coöperating with the named contact, and means acting on alternate inthrusts of 5 the plunger for holding it in engagement with the contact and for releasing it from such engagement.

2. In a combined electric connector and switch, in combination, a socket, a fixed 10 abutment therein, a spring-advanced contact carried by the abutment, a spring-retracted terminal plunger reciprocable in the socket and coöperating with the named contact, a 15 detent for holding the plunger in engagement with the contact, and cams acting on the plunger to engage it with the detent and to release it from such engagement, respectively, on alternate inthrusts of the plunger.

3. In a combined electric connector and 20 switch, in combination, a socket, a fixed abutment therein, a spring-advanced contact carried by the abutment, a spring-retracted terminal plunger reciprocable in the socket and coöperating with the named contact, a 25 stud projecting laterally from the plunger, a detent for engaging the stud to retain the plunger in engagement with the contact, a cam for guiding the stud in position for engaging the detent as the plunger is thrust 30 inward, and a cam for guiding the stud out of such engaging position, such two cams being effective on alternate strokes of the plunger.

4. In a combined electric connector and 35 switch, in combination, a socket, a fixed

abutment therein, a spring-advanced contact carried by the abutment, a spring-retracted terminal plunger reciprocable in the socket and coöperating with the named contact, a conductor extending axially through the 40 plunger, a seat for the retracting spring mounted on the inner end of the plunger, a disk swiveled on the conductor back of the spring seat and having a radial stud, a detent for engaging the stud to retain the 45 plunger in advanced position, a cam for guiding the stud as the plunger moves inward into position for engaging the detent, and a cam for guiding the stud out of such position on the next succeeding inthrust of 50 the plunger.

5. In a combined electric connector and switch, in combination, a socket having a contact element, a terminal plug interfitting and reciprocable in the socket and coöperating with the contact element thereof, a spring for forcing the plug outward, a stud projecting laterally from the plug, an aperture in the wall of the socket for receiving the stud, a bridge crossing the aperture and having a recess in its inner margin for receiving the stud, the end portions of the bridge being outwardly bowed to permit the passage of the stud, the socket aperture and the edges of the middle portion of the bridge 60 being configurated to form cams for guiding the stud to the bridge recess and in line with the ends of the bridge on alternate inthrusts of the plug.

CARL BRAMMING.
